CLAIM

The ornamental design for a skate guard as shown and described.

DESCRIPTION

1. Skate guard

1.1: Front

1.2: Right

1.3: Top

1.4: Bottom

1.5: Perspective

1.6: Cross sectional

1.7: Cross sectional

1.8: Enlarged

This article is a guard that covers the blade of a skate; two symmetrical members are connected by a spring member; the back view and left view of this design is omitted because the back view and the left view is respectively symmetric to the front view and the right view; the reproduction 1.6 is the longitudinal cross-sectional view taken through left side to right side; the reproduction 1.7 is the longitudinal cross-sectional view taken through front side to back side; the reproduction 1.8 is the enlarged view showing the lower part of the reproduction 1.2. The areas surrounded by the broken line in the reproduction 1.3 form no part of the claimed design. The broken line showing of the skate guard is for the purpose of illustrating portions of the article that forms no part of the claimed design.
